UNITED STATES PATENT OFFICE.

ADOLF MARTIN, OF TRENTON, NEW JERSEY, ASSIGNOR TO JESSE DEAN, INCORPORATED, OF TRENTON, NEW JERSEY.

DESIGN FOR A SURFACE DECORATION FOR CHINA, GLASS, OR LIKE ARTICLES.

56,984.

Specification for Design.

Patented Jan. 25, 1921.

Application filed August 4, 1920. Serial No. 401,275. Term of patent 7 years.

To all whom it may concern:

Be it known that I, ADOLF MARTIN, a citizen of the United States, residing at Trenton, in the county of Mercer and State of New Jersey, have invented a new, original, and ornamental Design for a Surface Decoration for China, Glass, or like Articles, of which the following is a specification, reference being had to the accompanying drawing, forming a part thereof.

The figure is a face view of a surface decoration showing my new design.

I claim:

The ornamental design for a surface decoration for china, glass, or like articles as shown.

ADOLF MARTIN.
